Application December 30, 1949, Serial No. 136,043

3 Claims. (Cl. 139—38)

1

The present invention relates to looms adapted to weave terry or cut pile fabrics.

In co-pending application Serial No. 123,545, filed October 26, 1949, now Patent No. 2,547,824, granted April 3, 1951, there is disclosed a loom of the character set forth above in which a reciprocable carriage, carrying a set of hooks, is periodically displaced from an inoperative into a thread engaging position in which the hooks engage certain warp threads to draw them into loops, the latter being then firmly anchored in the fabric by one or more traverses of the shuttle occurring while the carriage is retracted in inoperative position. In the particular form of machine disclosed, the carriage is normally held in its inoperative position by a retaining mechanism controlled in suitable manner, e. g. from a dobby-operated harness lever, so as to become automatically inoperative in timed relationship with the movements of the lay or batten so that, during certain reciprocations of the lay, the carriage is enabled to carry out a similar reciprocatory movement at the end of which it returns to its inoperative position. The release of the carriage from its retaining mechanism and its restoration to inoperative position is effected by the lay itself and springs are provided which, upon each such release, cause the carriage to follow the movement of the lay for a single reciprocatory cycle.

An object of the present invention is to provide, in a loom similar to the one described above, means for more positively displacing a hook-carrying member at intervals properly timed in relation to the movement of the lay.

Another object of this invention is to provide, in a loom of the character set forth, means for reciprocating a hook bar with respect to the threads of a fabric in such manner as to avoid obstruction, by the hook bar and associated mechanism, of large parts of the portion of fabric just completed, thereby enabling the operator to detect irregularities without undue waste of time and materials.

A further object of the instant invention is to provide a more compact mechanism for reciprocating a hook bar which will not materially add to the over-all dimensions of a conventional loom to be thus equipped.

Still another object of the invention is to provide novel feed means for advancing the pile warp to be drawn into loops by the hook bar.

To accomplish the above objects, and others which will subsequently appear, the invention provides, essentially, a hook bar swingable

2

mounted for reciprocating movement relative to the pile warp threads, and mechanism for reciprocating the hook bar at predetermined intervals in timed relation to the movements of the lay.

The invention will be described with reference to a preferred embodiment, shown in the accompanying drawing, in which:

Fig. 1 is a front elevation of a loom according to the invention;

Fig. 2 is a sectional elevation taken on the line 2—2 of Fig. 1;

Fig. 3 is a side elevation, on a larger scale, of part of the loom illustrated in Figs. 1 and 2, showing the hook bar and its reciprocating mechanism in operative and inoperative position; and

Fig. 4 is a top plan view of the assembly shown in Fig. 3.

Referring first to Figs. 1 and 2, there is shown 20 a machine 20 comprising a frame 21 whereon are supported the various elements of a conventional horizontal loom of the Northrop type, including the warp beam 22, the take-up roll 23, guide rollers 24, 25, 26, the lay 27 pivotally supported by its swords 42, 142 on a shaft 28, a set of dobbies 29 co-operating with harness levers 30 for selectively operating various harnesses such as shown at 31a, 31b, 31c, these harnesses being controlled through wires 33a, 33b, 33c passing over rollers 34a, 34b, 34c, and a motor (not shown) 30 which actuates all of these elements in a manner well known per se. Weft threads, supplied from suitable spools (not shown), form fillings 110 in the shed 90 which in turn is formed by two sets of warp threads 90a and 90b, these warp threads 35 passing from the beam 22 over guide rollers 24, 25, around rails 89, through the heddles of harnesses 31a, 31b, respectively, through the reed of the lay 27 and, after having been turned into a fabric 38, around guide roller 26 and deflection roller 112 to the take-up roll 23.

A continuously rotating cam shaft 41, serving to impart motion to the picker sticks 32, 132 in a conventional manner not further illustrated, carries a pinion 43 which drives, via an idler gear 44 mounted on a stud shaft 45, a gear 46 which is fixed to a timing shaft 47, the latter carrying a pair of cams 48, 148 (see also Figs. 3 and 4). A pair of rollers or cam followers 49, 149, each held between two parallel arms of a respective lever 50, 150, ride these cams to impart an intermittent oscillatory motion to the levers 50, 150 which are pivoted at 51, 151 to a respective projection 52, 15 of the frame 21; these two 55 levers are of S-shaped configuration and are

urged upwardly by springs 53, 153 maintaining their rollers 49, 149 in contact with the cams 48, 148, the two springs being anchored to the frame 21 at 54, 154.

The levers 50, 150 are pivotally linked by means of a connecting rod 55 extending across frame 21, to a pair of upwardly extending arms 56, 156 each of which is linked to a respective oscillating lever 57, 157 at 58, 158. A pair of standards 59, 159, secured to the frame 21 adjacent the two ends of its breast beam 40, respectively support a pair of bearings 60, 160 having short shafts 61, 161 journaled therein. Levers 57, 157 are pivotally mounted on standards 59, 159 at 62, 162. Each of these levers is connected over a respective link 63, 163 to an arm 64, 164 respectively keyed to shafts 61, 161. The arms 57, 157, 64 and 164 consist each of a pair of parallel members, similar to levers 50, 150, as best seen in Fig. 1.

Depending from and keyed to the shafts 61, 161 are a pair of swinging arms 65, 185 which are interconnected by a beam 66; the elements 65, 185, 66 together constituting a support 75 for a hook bar 70, carrying a set of hooks 105, which is secured to the beam 66. The hooks 105 may be of the character described in the above-identified application, or in applications Serial Nos. 129,572 and 129,573, filed November 26, 1949, and are shown to comprise a bill portion 106, lying substantially in the horizontal plane, and a vertical fin 109.

Supported on a pair of uprights such as 181, which rise from the rear of the frame 21, are a feed roller 83, a co-operating presser roller 84, a guide plate 85 and a deflecting roller 86, as well as a pair of brackets such as 182 in which there are journaled two further rollers 76, 77. Guide plate 85 is provided with apertures 87 through which pass respective threads 90c, representing the pile warp from which the loops are to be formed. The threads 90c, which may be somewhat heavier than the ground warp 90a, 90b and which are supplied by separate spools or the like, not shown, enter between the feed roller 83 and the presser roller 84, thence pass around rollers 76 and 77 which cause them to travel along a short horizontal run on which they traverse the eyes of individual riders 78 forming part of a stop-motion arrangement, and after passing around roller 86 and guide rails 89 enter the heddles of harness 31c. These threads, therefore, form part of the shed 90 previously referred to.

Mounted on the shaft 91 of feed roller 83 is a gear 92 which meshes with another gear 93 mounted on a stud shaft 94. A block 95, loosely pivoted on the stud shaft 94, carries a pawl 96 which is pivoted to the block 95 at 97. Pawl 96 co-operates with a ratchet 98, fixed to the stud shaft 94 so as to be rigid with gear 93, and is held in contact with the teeth of the ratchet by means of a suitable spring (not shown). The end of roller 83 opposite gear 92 is embraced by the jaws of a brake member 88 which is pivoted to the frame 21 at 88 and frictionally engages the roller 83 to prevent overrunning and maintain the threads 90c at a certain tension.

A rod 100 extends forwardly from the block 95 and rests on a cam 101 fixed to the shaft 61. A spring 102, secured to brace member 67 of the frame 21 of which only the companion member 167 is shown in Fig. 2, acts upon the rod 100 to maintain its front end in contact with the periphery of the cam 101.

The cam shaft 41 also carries, in addition to pinion 43, a gear 68 which meshes with another gear 69, the ratio of the teeth of these two gears being 2:1. Gear 69 sits on a crank shaft 71 which oscillates the lay 27 by means of connecting rods 72, 172 engaging the lay swords 42, 142. It will thus be seen that the lay executes two reciprocating movements during each rotation of cam shaft 41 and, with the number of teeth of gear 46 being n times that of the pinion 43, the timing shaft 47 completes a rotation after the lay has oscillated $2n$ times. Each of the cams 48, 148 is formed with a depression, shown at 174 for the cam 148 (Fig. 2), which is positioned to register with the corresponding roller 49, 149 at a time when the lay 27 is in its retracted position shown in Fig. 3 and in full lines in Fig. 2.

The operation of the mechanism described above is as follows:

20 Normally, i. e. when the rollers 49, 149 ride the circular portions of the peripheries of their respective cams 48, 148, the linkages 50, 58, 57, 63, 64 and 150, 156, 157, 163, 164 are in the position shown in Fig. 2 and in dotted lines in Fig. 3. The carriage 75 is then in its at rest or inoperative position, also shown in Fig. 2 and in dotted lines in Fig. 3. In this position of the carriage, the hooks 105 are moved out of the path of the warp threads which form the shed 90, rising and falling under the control of their harnesses 31a, 31b and 31c. After a number of traverses of the shuttle (not shown) to produce the fillings 110, followed by the beating-up motion of the lay 27 which oscillates between its two positions shown in full and in dotted lines in Fig. 2, the peripheral depressions of the cam 48, 148 approach the riders 49, 149, whereupon springs 53, 153 draw the levers 50, 150 upwards into the position illustrated in full lines in Fig. 3. Hook bar 70 is thereby swung into its rear-most or operative position in which its hooks 105, by proper synchronization with the dobby-actuated wire 33c, engage respective threads 90c which just then are in the raised position shown in Figs. 2 and 3. It will be noted that harness 31c raises the threads 90c above the highest position of the ground warp threads 90a or 90b, so that the hooks 105 will not interfere with these latter threads.

50 An instant later, and before the lay 27 has yet begun to move forward, the levers 50, 150 are again cammed downwardly and the hook bar support 75 returns to its normal position, the hooks 105 entraining respective threads 90c. The approximately simultaneous descent of harness 31c now forms the entrained thread portions into loops which by the subsequent traverses of the shuttle become firmly anchored in the fabric 38. It may be noted that, inasmuch as the restoring movement of the hook bar 70 is effected by a displacement of the rollers 49, 149 through the respective cams associated therewith, any collision between the hooks 105 and the reed of the lay 27 will be positively prevented.

55 When the support 75 and its operating linkage are in their normal position, the rod 100 rests on the highest point of its cam 101 as illustrated in Fig. 2. When the hook bar is now rotated, cam 101 rotates with it and allows spring 102 to pull the rod 100 down, thereby causing the pawl 96 to pass freely over a number of teeth of ratchet 98. As the hook bar returns to its normal position, the rod 100 is raised by the cam 101 and causes the pawl 96 to rotate the ratchet 98 counterclockwise, as viewed in Fig. 2.

thereby entraining the gears 93, 92 as well as the feed roller 83 to impart a positive feeding movement to the threads 90c during the time when they are entrained by the hooks 105. It may be mentioned that between movements of the hook bar, i. e. when no loops are being formed, the feeding movement of the fabric (due to rotation of rollers 26 and 23) also entrains the pile warp threads 90c, causing roller 83 to rotate in such sense that ratchet 98 passes unhindered under the tip of pawl 96. The threads 90c are thus held under a substantially invariable tension which, in the absence of a defect causing a break in one or more of the threads, will prevent their riders 78 from dropping to actuate the stop-motion arrangement.

It will, of course, be understood that each hook 105, when the hook bar 70 swings inwardly toward the lay 27, drops the loop previously formed thereon before again engaging a thread 90c; this dropping may be accomplished by letting the loop slide off the bill portion 106 or by cutting the loop in two, depending on whether it is desired to form terry or cut pile fabrics.

Although a single embodiment of the invention has been particularly disclosed, it should be understood that the description thereof has been given merely by way of illustration and that the same may be modified in various ways without departing from the spirit of the invention within the scope of the appended claims.

What is claimed is:

1. A machine for making fabrics with loops thereon, comprising sources of warp threads, continuously operable mechanism for weaving said warp threads into a fabric, said mechanism including a reciprocating lay and harness means for shedding said warp threads, a hook support swingably mounted forwardly of said lay for swinging movement toward and away from the latter, a set of hooks on said support aligned with and adapted to engage certain of said warp threads when the latter are selectively presented to said hooks by said harness means and said support is moved toward the lay, a pivoted operating lever, link means connecting said lever to said support for swinging the latter, spring means connected to said lever to continuously urge the latter in the direction effecting movement of said support toward the lay, a cam follower on said operating lever, a rotatable cam

engaging said cam follower to resist the action of said spring means and being formed with a depressed portion permitting movement of said lever in the spring urged direction only during a selected interval of the rotation of said cam, and means rotating said cam in synchronism with said continuously operable mechanism so that said selected interval occurs only during certain of the reciprocations of said lay.

- 10 2. A machine according to claim 1, wherein said continuously operable mechanism includes a cam shaft, a crank shaft, transmission means driven by said cam shaft to rotate said crank shaft at twice the speed of said cam shaft, and link means coupling said lay with said crank shaft; and wherein said means rotating said cam is driven by said cam shaft and effects rotation of said cam at a fraction of the rotative speed of said crank shaft.
- 15 3. A machine according to claim 1; wherein said hook support includes a rock shaft concentric with the axis of movement of the support; and further comprising feed means for said certain warp threads including a pair of rollers between which said certain warp threads extend, one of said rollers constituting a feed roller and having ratchet means coupled therewith, pawl means displaceable in two directions relative to said ratchet means for entrainment of the latter upon displacement of said pawl means in one of said two directions only, an actuating lever carrying said pawl means, and a cam fixed on said rock shaft to engage said actuating lever so that said pawl means is displaced in step with the movements of said hook support.
